GASEOUS DISCHARGE TUBE

Stanley G. Klumb, Milwaukee, Wis.

Application April 10, 1941, Serial No. 387,966

3 Claims. (Cl. 250—27.5)

This invention relates to gaseous discharge tubes and refers particularly to discharge tubes of the type employed in electric fence controllers for regulating the application of an electric charge onto the fence.

In certain types of electric fence controllers a gaseous discharge tube is connected in the circuit in such a manner as to fire or discharge at regular intervals and thus spontaneously and intermittently apply an electric impulse or charge on the fence.

The success of these controllers depends largely upon the ability of the tube to maintain the desired timing over long periods of usage and to withstand the destructive arcing which takes place between its electrodes. Exhaustive tests with gaseous discharge tubes heretofore available proved them to be wholly incapable of the strenuous service which a fence controller demands.

Heretofore both electrodes of the tube were formed of metal and as a consequence, the inevitable sputtering at the negative electrode during discharge of the tube volatilized and decomposed this electrode; and as a result a black oxide was deposited on the walls of the tube. This not only destroyed the negative electrode, but altered the firing rate of the tube as the decomposition of the electrode was accompanied by an inexplicable phenomenon which sometimes increased the gas pressure within the tube and at other times decreased the pressure.

With the above and other objections to gaseous discharge tubes heretofore available in mind, this invention has as a general object the provision of a tube which may be used successfully in electric fence controllers.

More specifically it is an object of the present invention to provide a gaseous discharge tube having a negative electrode which continuously restores itself to its initial condition.

These objectives are realized through the use of mercury for the negative electrode. The continual bombardment of the negative electrode by the ions leaving the positive electrode may vaporize the mercury to some extent but the objectionable results hereinbefore noted are not encountered as condensation of the mercury vapor continually restores it to its original liquid state and causes it to drip back into the pool comprising the negative electrode.

Inasmuch as the use of mercury for the negative electrode enables the tube to withstand the severe punishment it undergoes during use without change of its constants it is thus possible to set its firing time by predetermined spacing of

its electrodes and by regulating the pressure within the tube. With this objective in view, it is, therefore, another object of this invention to provide a tube so designed that the spacing between the electrodes remains substantially constant throughout a wide range of angular displacement to which the tube may be subjected in use and wherein the pressure within the tube may be adjusted to the desired degree by the admission of a proper amount of inert gas (such as argon) after evacuation of the tube.

Inasmuch as tubes used in electric fence controllers and for similar purposes are subjected to a wide range of temperature differential the gas used must be capable of retaining its characteristics. It is therefore a further object of this invention to provide a tube of the character described wherein the gas content is helium.

While the vaporization of the mercury which occurs as a result of its continual bombardment does not affect the constants of the tube, it may be desirable to keep the arc from striking the glass side wall, as continual bombardment at this point might weaken the tube and cause immature breakdown.

It is, therefore, another object of this invention to provide a novel bottom insert for the tube formed of suitable refractory material and designed to hold the quantity of mercury required for the negative electrode in a manner spaced from the side wall of the tube as long as the tube is held somewhere near upright.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates two complete examples of the physical embodiment of the invention constructed according to the best modes so far devised for the practical application of the principles thereof, and in which:

Figure 1 is a side view with parts broken away and in section illustrating one form of this invention; and

Figure 2 is a view similar to Figure 1 illustrating another embodiment of this invention.

Referring now particularly to the accompanying drawing in which like numerals indicate like parts, the numeral 5 designates a glass tube or

envelope closed at both ends and mounted in a base 6 of suitable insulating material.

The base is provided with two prong-like terminals 7 and 8 adapted to engage in a suitable socket by which the tube may be connected in an electric circuit.

Disposed within the tube are two electrodes 9 and 10 spaced apart to provide a spark gap across which the tube fires when the voltage impressed on its electrodes is in excess of the critical value.

The electrode 9, which is the negative electrode and which receives the bombardment of the ions during discharge of the tube, consists of a puddle of mercury. The other positive electrode 10 is formed of a metal which will not amalgamate with mercury and which has sufficiently high density to preclude release of trapped gases. Ferrous metals have proved satisfactory and Swedish iron has been found exceptionally good.

In the sense that it is not flowable or fluid like the mercury electrode 9, the electrode 10 is solid, and where this term is used in the claims it is to bring out this distinction.

Except for the manner in which the puddle of mercury constituting the negative electrode is held within the tube and the shape of the positive electrode 10 and the specific type of ferrous metal of which it is made, both embodiments of the invention illustrated are the same.

In both instances the positive electrode is supported from the dome-shaped top of the tube by means of a wire 11 passing through the tube wall. The wire 11 should have substantially the same coefficient of expansion as lead glass which is used for the tube. Dumet wire meets this requirement.

In the embodiment of the invention shown in Figure 1 the Dumet wire 11 extends down through the tube wall to be connected to and support electrode 10 which in this instance is a tungsten wire.

Except for its lower tip which forms the electrode proper, this tungsten wire is covered with a suitable insulating sheath 12. In each instance the wire 11 is fused to a glass bead 13 prior to its assembly with the tube, and then the bead is fused to the tube.

In the other embodiment of the invention the electrode 10 is a round rod or piece of Swedish iron having its lower end rounded for a purpose to be hereinafter described.

In the construction shown in Figure 1 the puddle of mercury 9 fills a central well 14 formed in a ceramic insert 15. The top wall of this insert slopes upwardly from the edge of the well to the periphery of the insert so as to at all times guide the mercury toward and assure its accumulating in the well 14.

The insert 15 substantially fits the bottom of the tube and is secured in place by a wire lead 16 having one end fixed to an iron washer 17 seated in the bottom of the well and passing through the tube to have its opposite end soldered to the prong 7.

The other prong 8 has one end of a wire 18 fixed thereto. This wire passes out through a hole in the side of the base and extends upwardly along the exterior of the tube to be connected as at 19 to the wire 11 and consequently the electrode 10.

In the construction shown in Figure 2 the terminal connections for the electrodes are the same as that of Figure 1, but in place of the insert 15 a larger quantity of mercury is employed and it pools directly in the bottom of the tube as shown.

The rounded lower end of the positive electrode 10 assures the maintenance of the desired spacing between the electrodes even though the tube may be inclined a substantial distance from vertical. As will be apparent the distance between the surface of the mercury and the nearest portion of the electrode 10 remains substantially the same throughout a relatively wide angle of inclination.

10 With the construction of Figure 1 in which the electrode 10 is substantially a point, this problem does occur.

This latter construction, however, has the advantage of keeping the arc from striking the glass which might cause breakage.

15 In making the tube, after the various elements are assembled in the manner described, the tube is baked to drive off the occluded gases from the walls of the glass, the mercury pool and all internal parts. The tube is then evacuated to as nearly a perfect vacuum as possible and while the tube is physically connected to the vacuum source but shut off therefrom a desired amount of helium or other suitable inert gas is admitted. Thereafter the tube is sealed in the customary manner which generally leaves a tip 20 and disconnects it physically from the vacuum source.

20 Obviously by controlling the amount of the gas admitted to the tube its internal pressure may be predetermined. The critical value of the tube, or, in other words, the voltage required to be impressed across its terminals to cause it to fire, depends primarily upon two factors, one the spacing between the electrodes, and two the internal pressure of the tube.

25 The spacing of the electrodes may vary slightly from the desired amount in different tubes, but this is of no consequence as will be seen. The important thing with respect to this factor is that the spacing will not change during usage.

30 The gas pressure, the second factor, is individually set for each tube in the following manner: After evacuating and while the gas admission takes place the tube is connected in an electric circuit consisting of a condenser across which the tube is connected and a unidirectional pulsating voltage source connected to charge the condenser. A voltmeter connected preferably across the condenser indicates the potential on the condenser at which tube discharge takes place. With a slight amount of inert gas in the tube, its resistance is low and hence firing of the tube is frequent and the breakdown potential as measured by the voltmeter is low. With increase 35 in gas pressure the tube's resistance rises and so does its critical value. When the voltmeter indicates the desired flash voltage gas admission is stopped and thereafter the tube will always fire at the value last indicated.

35 In view of the wide temperature range that tubes of this type are subjected to in use, the gas used must not be easily affected by temperature. Helium is known to be stable in this respect, but from much experiment it was learned that unless the helium is spectroscopically pure the walls of the tube become plated with mercury and the gas pressure varies.

40 With spectroscopically pure helium no changes take place in the tube constants when the tube is used for such purposes as electric fence controllers where the temperature ranges from summer heat to extreme winter cold.

45 As noted hereinbefore the ions leave the positive electrode 10 during discharge of the tube, but inasmuch as the negative electrode is formed of

mercury its resultant bombardment in nowise affects the constants of the tube.

While it is true that such bombardment causes the mercury to vaporize, this merely results in condensation of the mercury vapor which then drips back into the pool to restore the negative terminal to its initial condition.

By the constants of the tube is meant the space between the electrodes and the pressure of the gas within the tube.

From the foregoing description taken in connection with the accompanying drawing it will be readily apparent that this invention provides a gaseous discharge tube capable of withstanding the strenuous service imposed upon such tubes by their use in electric fence controllers, and that the tube is extremely simple and rugged in construction.

What I claim as my invention is:

1. A gaseous discharge tube suitable for controlling the discharge of a condenser in a condenser discharge type electric fence controller wherein the tube must be capable of successfully withstanding relatively heavy loads without change in its factors determining the firing voltage of the tube comprising: an envelope from which air has been evacuated; means for mounting the envelope in an upright position; a pool of mercury in the bottom of the envelope providing a cold cathode; a solid metal electrode providing an anode; means supporting the metal electrode in a fixed position in the envelope; the end of the electrode adjacent to the surface of the mercury being of such size and shape that the spacing between it and the mercury remains substantially constant throughout a relatively wide range of possible inclination of the envelope from its intended upright position; and an inert gas in said envelope, the pressure of which determines the firing voltage of the tube with a given spacing between the anode and cathode, said inert gas having a relatively low coefficient of expansion so that the gas pressure remains substantially constant during varying temperature conditions, and said gas being resistant to absorption by the mercury and having good spark quenching characteristics.

2. A high voltage discharge device suitable for controlling the discharge of a condenser in a condenser discharge type electric fence controller wherein the condenser spontaneously dis-

charges through the device to place an effective shock on the fence comprising: a discharge tube having an envelope from which air has been evacuated; means for mounting the envelope in an upright position; means for firing and controlling discharge of the tube including a pair of spaced apart electrodes and an inert gas inside said envelope, one of said electrodes being a pool of mercury in the bottom of the envelope and providing a cold cathode for the tube, the other electrode being of solid metal and being rigidly mounted in the envelope and having its portion adjacent to the surface of the pool of mercury of such size and shape that the spacing between it and the mercury remains substantially constant throughout a relatively wide range of possible inclination of the envelope from its intended upright position, and said inert gas being spectroscopically pure helium, the pressure of the helium and the spacing of the electrodes being such as to permit firing and discharge of the tube only upon impression of a predetermined high voltage across the electrodes of the tube and to at all other times prevent arcing between said electrodes.

3. A gaseous discharge tube suitable for controlling the discharge of a condenser in a condenser discharge type electric fence controller wherein the tube must be capable of successfully withstanding relatively heavy loads without change in its factors determining the firing voltage of the tube comprising: an envelope from which air has been evacuated; means for mounting the envelope in an upright position; an insert in the bottom of the envelope formed of refractory material and having a concave top surface leading from the side walls of the envelope and converging down to the mouth of an open central well in the insert; a conductor leading from the bottom of the well through the wall of the glass envelope to the exterior thereof; a quantity of mercury in said well providing a cold cathode for the tube, said well holding the mercury spaced from the glass walls of the envelope to thereby preclude the arcs which occur during firing of the tube from striking the glass; and an anode supported from the upper portion of the tube and extending down toward the mercury but spaced therefrom.
